UNITED STATES PATENT OFFICE.

JESSE W. DOBLE, OF SAN FRANCISCO, CALIFORNIA, ASSIGNOR TO DOBLE LABORATORIES, OF SAN FRANCISCO, CALIFORNIA, A CORPORATION OF CALIFORNIA.

STEAM-POWER-PLANT CONTROL.

Application filed December 13, 1919. Serial No. 344,741.

To all whom it may concern:

Be it known that I, JESSE W. DOBLE, a citizen of the United States, and a resident of the city and county of San Francisco, State of California, have invented a certain new and useful Steam-Power-Plant Control, of which the following is a specification.

The invention relates to the control of the fire in liquid fuel burners when used in connection with steam boilers or other heat absorbing medium containing devices and to the control of water supply to steam boilers.

The objects of the invention are many, as will appear hereinafter.

One of the objects of the invention is to provide a control system for liquid fuel burners of heat absorbing medium containing devices, in which the amount or volume of the fire is varied in accordance with changes in temperature or pressure within the device.

Another object is to provide means for varying the fire while maintaining the proportion of air to liquid fuel in the combustible mixture substantially constant, thereby providing an efficient and completely combustible mixture, regardless of the size of the flame.

Another object of the invention is to vary the feed water intake in accordance with variations in temperature or pressure or both within the steam boiler.

The invention possesses many other objects and features of advantage, some of which, with the foregoing, will be set forth at length in the following description, where I shall outline in full, that form of the invention which I have selected for illustration in the drawings accompanying and forming part of the present specification. In said drawings, I have shown one specific embodiment of my generic invention, but it is to be understood that I do not limit myself to such form, since the invention as expressed in the claims may be embodied in a plurality of forms.

The drawings show the invention as embodied in a steam boiler control system, but it is to be understood that the invention is not limited to use with steam boilers, but may be employed in connection with hot water heaters, house heaters and other heat absorbing medium containing devices. The

steam boiler shown in the drawings is particularly adapted for use on steam propelled vehicles, such as trucks, tractors and automobiles, in which use widely varying steam demands are made on the boiler. In such use, the control system operates to maintain, or to tend to maintain, a substantially constant temperature and pressure within the boiler. The fixed temperature and pressure may not be exceeded, although in instances of extremely heavy steam demand, the pressure or temperature may fall slightly. This control is accomplished by variations in air and liquid fuel, forming the combustible mixture and variations of the rate of admission of the feed water.

Referring to said drawings:

Figure 1 is a diagrammatic representation of a steam boiler provided with the control system of my invention.

Figure 2 is a side elevation of a combined steam boiler and engine, the boiler being partly broken away to disclose the burner construction.

Figure 3 is a vertical section through the blower chamber and pressure control devices, also showing the air valve.

Figure 4 is a vertical section of the pressure operated control device, taken on the line 4-4, Figure 3.

Figure 5 is a top view of the pressure operated control device with the cover plate removed.

Figure 6 is a vertical section of the pressure control device, taken on the line 6-6, Figure 3.

The steam boiler 2 is provided with a combustion chamber 3 in which the fire burns and from which it discharges into contact with the boiler tubes 4. The liquid fuel for combustion is fed through a suitable conduit 5 into the rapidly rotatable cup 6, from which it discharges in a spray. Any suitable liquid fuel may be employed, such as kerosene or distillate. The cup 6 is rotated by an electric motor 7 and arranged on the motor shaft is a blower 8, enclosed in the housing 9. The air from the blower passes from the blower chamber into the channel or passage 12, which is in thermal communication with the combustion chamber, thence through the passage 13, surrounding the combustion chamber, and thence into the

chamber adjacent the rapidly rotating cup, where it is mixed with the fuel spray, producing combustible fuel mixture. The proportion of air and fuel is preferably such that a completely combustible mixture is produced.

The passage 12 is wider than the blower chamber 9 and is connected therewith by a flaring passage 14. Arranged in the air passage 10 and preferably at the junction of the passage 14 with the passage 12 is a damper or flat butterfly valve 15 which is operative to vary the area of the air passage and hence the volume of air passing into the combustion chamber. The valve 15 is caused to operate by variations in pressure in the boiler, an increase in pressure above a predetermined pressure causing the valve to move to constrict the air passage and a decrease in pressure from an excessive pressure causing the valve to move to open the air passage. The valve is mounted on a shaft 16 journaled in the casing, and secured to an extension of the shaft is an indicator 25 17 which shows the position of the valve.

Mounted on the blower casing, at one side thereof, is a cylinder 18 having a bottom therein upon which the spring 21 bears. The cylinder is closed at the top by a head 22 having a smaller cylinder 23 formed integrally therewith. The cylinder 23 is provided with a nipple 24 for connection with a steam zone in the boiler, so that steam under boiler pressure flows into the cylinder 30 23. Disposed in the smaller cylinder is a piston 25, having an extension 26 which projects through an aperture in the bottom of cylinder 23 and which rests on the bottom of the cylinder 27. The upper end of the cylinder is flanged and rests on or engages the upper end of the spring 21. The spring, therefore, holds the piston 25 pressed upwardly, and when the steam pressure exceeds the spring pressure, the piston is depressed. Secured to the piston is an adjustable rod 28, provided at its lower end with a rack 29 in engagement with the gear 31 on the shaft 16. Depression of the piston for the limit of its movement closes the valve 15, so that practically no air passes into the combustion chamber.

Means operated by an increase in pressure are also provided for decreasing the fuel supply, the decrease of fuel supply varying with the increase in pressure. Mounted on the other side of the blower casing is a chamber 32, into which extends the adjustable length rod 33, provided on its lower end with a rack 34 in engagement with the gear 35 on the shaft 16. The rod 33 lies on the opposite side of the shaft from the rod 28, so that a downward movement of rod 28 causes an upward movement of rod 33 and vice versa. Arranged in the casing 32 is a rotary fuel valve 34' having inlet and

outlet connections 35' and 36 to which the fuel conduit 5 is connected. The valve is provided with a pin or projection 37 which lies in the groove of a collar 38 adjustably secured to the rod 33, so that as the rod 70 moves vertically, the valve is turned to vary the flow of fuel. When the rod 33 is in its lower position, the valve is fully open and as the rod raises, the valve is turned to restrict the flow of fuel. The fuel valve 75 is thus directly connected to the air valve, so that the supply of air and fuel are simultaneously varied and in preferably the same degree, so that a perfectly combustible mixture is always produced, regardless of the 80 size of the flame. The fire is, therefore, varied by variations in pressure in the boiler above a predetermined pressure.

Means operative by variations in pressure above a predetermined pressure, are also 85 provided for controlling the flow of feed water into the boiler. Feed water is forced into the boiler by the pump 41 which is directly connected to the engine which is operated by steam from the boiler. On its intake side, the water pump is provided with a solenoid operated valve 42 which is held open when the circuit of the solenoid 43 is closed. This valve is fully disclosed in the application of Jesse W. Doble, Serial No. 90 227,787, filed in the Patent Office on April 10, 1918. When the valve is held open, no water is pumped into the boiler by the pump. The solenoid circuit is normally open and means are provided for closing 100 the circuit when a predetermined excessive pressure is reached in the boiler. Disposed in the casing 32 above the rod 33 are a pair of normally separated contacts disposed in the circuit of the solenoid 43. The upper contact 44 is stationary and is secured to the binding post 45. The lower contact 46 lies immediately below the upper contact and is mounted on a metallic lever 47 pivoted to the shank 48 of the binding post 49. The lever 47 is disposed above the end of the rod 33 and is pressed downward by a spring 51. When the rod 33 is moved upward, due to an increase in boiler pressure, it contacts with the insulator pad 52 on the lever 47 115 and raises the lever to close the contact in the solenoid circuit, thus opening the inlet valve and preventing the flow of feed water into the boiler. Temperature operated means are also provided for closing the 120 solenoid circuit and will be described hereinafter, the pressure operative means serving to close the solenoid circuit not only on an increase in pressure due to steam generation but also due to the pressure created by the feed pump, as for instance when the vehicle is traveling down a long grade, and the engine is turning over, operating the feed pump.

Means are also provided for shutting off 125

the fuel supply entirely and for opening the circuit of the motor 7 when the pressure within the boiler reaches a predetermined excessive value. Disposed in the fuel line 5 is a chamber 53 through which the fuel passes. The outlet from this chamber is controlled by a valve 54, to the stem of which is secured a core 55, surrounded by a solenoid 56. The solenoid circuit is normally closed, so that the valve 54 is normally held in the raised position, permitting the flow of fuel. When the solenoid circuit is opened the valve falls, cutting off the supply of fuel to the burner and when the circuit 10 is subsequently closed, the valve is again raised. The solenoid circuit 57 is provided with two normally closed breaks in series, one of which is opened by an excessive pressure and the other of which is opened by an 15 excessive temperature. The pressure controlled break is arranged in the casing 32, and comprises a fixed contact 58 and a contact 59 carried by the spring pressed lever 61. Passing through the lever 61 is an adjusting screw 62, the lower end of which lies in the path of the disc 63, adjustably secured to the rod 33. When the rod is raised, the disc contacts with the lower end 20 of the screw 62 and raises the lever 61 to open the solenoid circuit. Binding posts 25 64 and 65 for the contacts 58 and 59 respectively are arranged on the exterior of the casing 32. The screw 62 is provided with a milled head 66 which is engaged by a spring 30 67 to hold the head against accidental rotation after the screw has been moved to the proper setting.

Secured to the stem of the fuel valve 54 is a contact 68 which is normally in contact 35 with a fixed contact 69, both contacts being in the circuit of the motor 7. When the valve 54 drops to close the fuel supply, the contacts 68 and 69 are separated, opening the motor circuit.

40 Disposed in the circuit of the solenoid 56 is a normally closed break comprising the contacts 71 and 72. The contact 72 is stationary and the contact 71 is carried by an insulator disc 73 secured to a metallic rod 45 74 capable of varying its length under changes in temperature. The rod 74 is disposed in a metallic tube 75, having a lesser coefficient of expansion and preferably disposed within one of the boiler tubes. The 50 tube 75 is closed at its inner end and the rod is secured to the tube at its inner end. The rod is, therefore, subjected to boiler temperature and its length is varied in accordance with changes in such temperature.

55 An increase in temperature over a predetermined temperature causes the rod to lengthen to separate the contacts 71 and 72 and thereby open the circuit of the solenoid 56.

60 Means are also provided for holding the

valve 42 open when the temperature in the boiler is low, to prevent flooding the boiler. The solenoid 43 is provided with a circuit 76, in parallel with the pressure controlled circuit, and the circuit 76 contains a break 70 which is closed until the boiler temperature increases to a predetermined value. The disc 73 carries a contact 77, which, when the boiler is cold, contacts with the fixed contact 78 in the circuit 76, energizing the solenoid 43 and holding the valve open. When the temperature increases, the contacts are separated, the valve 42 is released and feed water is pumped into the boiler.

The motor 7 and the solenoids are energized by current from the storage battery 79, which is grounded on one side and which is connected on the other side to the various circuits, through the switch 81. Closing the switch places the whole system in operation 85 and boiler pressure and temperature are automatically regulated. The combustible mixture in the burner may be ignited in any suitable manner, such as by an electric spark, such as is shown in the application 90 for Letters Patent of John A. Doble, Serial No. 217,077, filed in the Patent Office on February 14, 1918.

I claim:

1. In a control system for a steam power plant, a liquid fuel burner for affecting a heat absorbing medium in which the pressure may be made to vary by an application of heat, a valve for varying the amount of air supplied to the burner, a valve for varying the supply of fuel to the burner, means responsive to the pressure of the heat absorbing medium for mechanically operating the air valve, and means responsive to the movement of the air valve for operating the fuel valve. 95
2. In a control system for a steam power plant, a liquid fuel burner for affecting a heat absorbing medium in which the pressure may be made to vary by an application of heat, a valve for varying the amount of air supplied to the burner, a shaft connected to the valve, means responsive to the pressure of the heat absorbing medium for operating the shaft, a valve for varying the supply of fuel to the burner, and a mechanical connection between the shaft and this latter valve. 100
3. In a control system for a steam power plant, a liquid fuel burner for affecting a heat absorbing medium in which the pressure may be made to vary by an application of heat, a rotary valve for varying the amount of air supplied to the burner, means responsive to the pressure of the heat absorbing medium mechanically connected to this valve, a valve for varying the supply of fuel to the burner, and a direct mechanical connection between the two valves. 110
4. In a control system for a steam power 115

- plant, a liquid fuel burner for affecting a heat absorbing medium in which the pressure may be made to vary by an application of heat, a rotary shaft, a valve fastened to the shaft for varying the amount of air supplied to the burner, means responsive to the pressure of the heat absorbing medium for rotating the shaft, a valve for varying the supply of fuel to the burner, and a crank connection between the shaft and the fuel valve.
5. In a control system for a steam power plant, a liquid fuel burner for affecting a heat absorbing medium in which the pressure may be made to vary by an application of heat, a blower for supplying air to the burner, an electric motor for driving the blower, a valve for controlling the supply of fuel to the burner, means responsive to a rise 15 in pressure in the medium for operating the valve so as to interrupt the flow of fuel, and means responsive to the operation of this valve for rendering the motor inoperative.
6. In a control system for a steam power plant, a liquid fuel burner for affecting a heat absorbing medium in which the pressure may be made to vary by an application of heat, a blower for supplying air to the burner, an electric motor for driving the blower, a valve for controlling the supply of fuel to the burner, an electromagnet for operating the valve, an electric control circuit for the magnet, means responsive to a rise 25 in pressure in the medium for altering the circuit so as to cause the valve to interrupt the supply of fuel, an electric circuit for the motor, and means operated by the electromagnet for controlling the motor circuit.
- 30 7. In a control system for a steam power plant, a liquid fuel burner for affecting a heat absorbing medium, a blower for supplying air to the burner, an electric motor for driving the blower, a valve for controlling the supply of fuel to the burner, means responsive to a rise 35 in temperature in the medium for operating the valve so as to interrupt the flow of fuel, and means responsive to the operation of this valve for rendering the motor inoperative.
8. In a control system for a steam power plant, a liquid fuel burner for affecting a heat absorbing medium, a blower for supplying air to the burner, an electric motor for driving the blower, a valve for controlling the supply of fuel to the burner, an electromagnet for operating the valve, an electric control circuit for the magnet, means responsive to a rise 45 in temperature in the medium for altering the circuit so as to cause the valve to interrupt the supply of fuel, an electric circuit for the motor, and means operated by the electromagnet for controlling the motor circuit.
- 50 9. In a control system for a steam power plant, a liquid fuel burner for affecting a heat absorbing medium in which the pressure may be made to vary by an application of heat, a valve for varying the supply of fuel to the burner, a valve for abruptly interrupting the supply of fuel, and means responsive to a rise in pressure for gradually closing the first valve and later for operating the second valve.
10. In a control system for a steam power plant, a liquid fuel burner for affecting a heat absorbing medium, a valve for gradually varying the supply of fuel to the burner, another valve for abruptly interrupting the supply of fuel, and means responsive to a rise in temperature of the medium for gradually closing the first valve, and later for operating the second valve.
11. The combination with a heat absorbing medium containing device, of a liquid fuel burner associated with said device, a conduit through which air is introduced into said burner, a valve arranged to vary the flow of air through said conduit, a spring loaded piston subjected to the pressure in said device and connected to said valve, a conduit through which fuel is introduced into the burner, a valve in said fuel conduit arranged to vary the flow of fuel therethrough, a second valve in the fuel conduit arranged to abruptly interrupt the flow of fuel therethrough, means operative by movement of the air valve for gradually closing the first fuel valve, and means operative by further movement of the air valve for operating said second fuel valve.
12. The combination with a heat absorbing medium containing device, of a liquid fuel burner associated with said device, a conduit through which fuel is introduced into the burner, a valve in said conduit adapted to vary the flow of fuel therethrough, a second valve in said conduit adapted to abruptly halt the flow of fuel therethrough, means operative by an increasing pressure in the device for gradually closing said first valve and then abruptly closing said second valve.
13. The combination with a heat absorbing medium containing device, of a liquid fuel burner associated with said device, a conduit through which fuel is introduced into the burner, a valve in said conduit adapted to vary the flow of fuel therethrough, a second valve in said conduit arranged to abruptly open and close said conduit, a solenoid for operating said second valve, and means operative by an increasing pressure in the device for gradually closing said first valve and then opening the solenoid circuit.
14. The combination with a heat absorbing medium containing device, of a liquid fuel burner associated therewith, a conduit through which fuel flows to said burner, a

casing to which said conduit is connected, a valve in said casing for controlling the flow of fuel through said conduit, a rod engaging said valve, a second valve in the conduit, 5 a solenoid for operating said valve, a circuit for said solenoid, normally engaging contacts in said circuit disposed in said casing adapted to be separated by said rod, and

means actuated by variations in pressure within the device for moving said rod.

In testimony whereof, I have hereunto set my hand at San Francisco, California, this 6th day of December, 1919.

JESSE W. DOBLE.

In presence of—
H. G. PROST.
